3 Claims. (Cl. 207—17)

1

The present invention relates to the hot extrusion of metals in an extrusion press.

It is known that this operation is carried out by placing a billet of the metal to be extruded inside a container open at both ends and by pressing on said billet by means of a ram entering one end of the container, thereby forcing the metal to pass through a die arranged at the other end.

This operation, such as normally and commonly effected, makes it necessary to leave in the container of the extrusion press, at the end of the operation, a certain length of the billet usually called a discard.

In order that the extruded product may be disengaged from the die, it is necessary to separate the discard from the rest of the product. Several methods have been proposed and used therefore amongst which the following may be mentioned:

(a) If the shape of the die and die-holder are suitable, for instance if the face which is turned towards the inside of the container is plane, the discard may be cut-off, after separating from the container the assembly consisting of the die, the extruded product and the discard. This possibility, however, is limited to non-ferrous metals and products with simple cross sections.

(b) It is also possible, after having removed the above mentioned assembly from the container, to pull the discard out of the die by clamping it in a vise and pulling it backwards, for disengaging a small part of the extruded product, which is then cut off. This method, however, is liable to cause trouble, particularly when the discs to be removed are thin or lubrication is defective.

(c) At the end of the extrusion operation, the extruded product may be cut, beyond the die, outside of the tools, the assembly formed of the discard and the die may be moved away from the press, and these two parts may be separated from each other outside the press by any known means. The press is thus rapidly available for the next operation, but such a method offers numerous technical disadvantages.

(d) The discard may also be made to adhere to the container, after which the die and the container are separated from each other, thus freeing a part of the extruded product which may then be cut off.

(e) Finally a stud may be provided on the working face of the ram or dummy block placed ahead thereof, said stud being adapted to pass through the discard and stopping the flow of metal through the die, thereby automatically severing the extruded product from the discard inside the die itself.

2

However, all these methods have the disadvantage of substantially slowing down the rate of production. Most often, the various operations described are carried out on the press itself, and should be finished before it is possible to pass on to the next extruding operation. Further, when any trouble occurs, which prevents the releasing of the die, such as, for instance, the seizing of the extruded product or discard against the die, the operation of the press has to be stopped until the tools have been freed.

An object of the invention is to provide means to do away with the disadvantages of the above mentioned methods by providing a special construction for the die-carrier or holder, i. e. the member holding the die at one end of the container, and forming at the same time a removable wall closing the said end.

A die holder according to the invention comprises two coaxial members each corresponding to a part of the height of the die, and fitting into each other, at least one of said members forming a wall for the container at the end thereof at which the die is arranged. This die-holder assembly has been provided with an axial, frusto-conical boring the wall generatrices of which converge towards the face of the die-holder which applies on the container, and are inclined on the axis of the die-holder by an angle which is slightly greater than the seizing angle of the metal or metals forming the die holder and die, the said boring being designed to receive the die which has a corresponding outer surface, a counter-die or the like being provided for holding the die in the said holder.

An embodiment of the device according to the invention has been shown by way of example in the accompanying drawings, in which:

Fig. 1 is a diametral sectional view of a die-holding block comprising a two-member die holder, a die and a counter-die.

Fig. 2 is a similar view showing an extruded bar at the end of the extruding operation, the two die-holder members having been moved away from each other.

Fig. 3 is a similar view, the block still being compact.

Referring to the drawings, the die holder A, which applies at the end of the container C, comprises two members 1 and 2, made of steel, assembled by conical fitting. Member 1 corresponds to the portion of the die-holder which applies on the container and closes the end thereof. In this assembly, there is provided a frusto-conical bore 3, the generatrices of which converge towards the free face of member 1, and are inclined

on the axis of the bore, by an angle slightly greater than 9°, which is the value of the seizing angle of steel. The die 4 has a corresponding outer surface which allows it to fit into the bore 3. It is held in the said bore 3, during the extruding operations, by a counter-die 5 provided with a central recess 6 for the passage of the extruded product.

With an extrusion press provided with such a die holder, two different manners of operating may be used for separating the discard from the extruded product at the end of an extrusion operation.

As shown in Figure 2, member 1 of the die-holder may be held by any suitable means, against the container and part 2, be moved away axially, the die 4 and counter-die 5 thus being carried away. The discard 8 is held by the member 1 on which it bears and the drawn bar 8 is sawn off in the plane S. The assembly formed by the member 1 and the discard 7 is removed from the container, the separation of said assembly offering no difficulty since the discard 7 simply rests against member 1, and in another operation which may take place outside the press, the die 4 can be separated from the extruded bar 8.

It will be realized that instead of moving member 2 with respect to member 1, the container being motionless, member 2 could just as well be held fixed and the container and member 1 moved away axially from member 2, which amounts to the same thing.

One may also, as shown in Figure 3, saw the drawn bar 8 in the plane S beyond the counter-die 5, remove from the press the whole assembly formed of members 1, 2, of the die 4 and of the discard 7, separate member 1 from member 2 by means of an auxiliary apparatus, and then separate, on the one hand, the discard 7 from member 1 and, on the other hand, the die from member 2.

The device of the invention thus makes it possible to separate without difficulty the discard and the extruded product from the die and die holder, even in cases where this operation is difficult such as in the case of a thin discard, of a discard jammed in the die-holder or in the die, or of an extruded product jammed in the die.

The present invention also has the advantage of reducing the duration of a complete extrusion operation, on the one hand by avoiding the above recalled troubles and on the other hand in a still more marked manner, by making it possible to separate the discard from die holder outside the press and by eliminating the necessity of passing back the extruded product through the die, which always is a delicate operation when dealing, for instance, with products which have been extruded at a high temperature, using glass as a lubricant.

What we claim is:

1. In a press for the hot extrusion of metals, comprising a container adapted to receive a billet of the metal to be extruded, and having two open ends, a die holder comprising a first annular metal member having two faces, one of which is shaped for fitting tightly into one of said open ends of said container thereby partly closing said end, and a first axial bore with a frusto-conical wall, the narrowest end of which lies on the side of said face which fits in the container, a recess in the face of said first annular member which is opposite that which fits into the container, and surrounding said first axial bore, and a second metal annular member, adapted to fit

into said recess, having a second axial bore with a frusto-conical wall adapted to extend the wall of the first axial bore in said first annular member when said first and second annular members are fitted into each other, an extrusion metal die having a frusto-conical outer wall, the frusto-conical surfaces formed by the walls of said bores in said first and second annular members and by the outer wall of said die having a same apex angle slightly greater than the seizing angle of the metal forming the die and the metal forming said first and second annular members, and a member adapted to hold the die in the bores in said annular members when said annular members are fitted into each other.

2. In a press for the hot extrusion of metals, comprising a container adapted to receive a billet of the metal to be extruded, and having two open ends, a die-holder comprising a first annular metal member, having two faces, one of which is shaped for fitting tightly into one of said open ends of said container, thereby partly closing said end, and a first axial bore with a frusto-conical wall the narrowest end of which lies on the side of said face which fits in the container, a recess in the face of said first annular member which is opposite that which fits into the container, and surrounding said first axial bore, said recess having a frusto-conical inner side wall, flaring towards the face of said first member which is opposite that which fits in the container, and a second annular metal member having an extension with a frusto-conical side wall adapted to fit into said recess, and having a second axial bore with a frusto-conical wall adapted to extend the wall of the first axial bore in said first annular member when said first and second annular members are fitted into each other, a metal extrusion die having a frusto-conical outer wall, the frusto-conical surfaces of the walls of said bores in said first and second annular members and of the outer wall of said die having the same apex angle slightly greater than the seizing angle of the metal forming the die and the metal forming said first and second annular members, and a member adapted to hold the die in the bores in said annular members when said annular members are fitted into each other.

3. In a press for the hot extrusion of metals, comprising a container adapted to receive a billet of the metal to be drawn, and having two open ends, one of said ends having an outwardly flaring, frusto-conical seat, a die-holder comprising a first annular metal member, having two faces, one part of one of said faces being frusto-conically bevelled outwardly for fitting on said frusto-conical seat of said end of the container, while the remainder of said face is bevelled inwardly and ends in a first axial bore with a frusto-conical wall, the narrowest end of which lies on the side of said face which fits into the container, a recess in the face of said first annular member which is opposite that which fits into the container, and surrounding said first axial bore, and a second annular metal member having an extension with a frusto-conical side wall adapted to fit into said recess, and having a second axial bore with a frusto-conical wall adapted to extend the wall of the first axial bore in said first annular member when said first and second annular members are fitted into each other, a metal extrusion die having a frusto-conical outer wall, the frusto-conical surfaces of the walls of said bores in said first and second annular members

and the outer wall of said die having the same apex angle, slightly greater than the seizing angle of the metal forming the die and the metal forming said first and second annular members, and a member adapted for holding the die in the bores in said annular members when said annular members are fitted into each other.
